SHEAR FOR CUTTING BILLETS, BEAMS, AND THE LIKE

Murray Renick, East Meadow, N.Y., assignor to Baldwin-Lima-Hamilton Corporation, Philadelphia, Pa., a corporation of Pennsylvania
Filed Dec. 4, 1958, Ser. No. 778,181
5 Claims. (Cl. 83—559)

This invention relates to shears for cutting metal, and more particularly to vertical shears of the so-called universal type for handling a great variety of materials such as billets, bars, angles, beams, channels, and other profiles.

Conventional shears of the above type normally have a lower knife which is in a fixed position on the shear housing or frame, and an upper knife which is rigidly secured to a knife actuator or ram. Thus, both knives are within the confines of the shear housing and all knife changes must be made within the shear proper. Such changes and the necessary realignment of the parts are extremely time consuming and cause the machine to remain idle while these steps are carried out, which results in a very considerable loss in production.

It has been proposed to provide a removable lower knife carrier sliding laterally out of the shear so that the lower knife or knives may be replaced outside the machine. The upper knife or knives, however, must still be changed within the confines of the shear where accessibility is limited so that the work requires much time. Likewise, the alignment of the upper and lower knives must be carried out within the shear. The machine is idle while the upper knives are changed and the parts are aligned so that the loss in production is still very considerable.

Another difficulty encountered in conventional shears of the above type is due to the fact that normally the lower knife is vertically fixed relative to the frame. In such arrangement, the material to be cut must be supplied to the shear at the fixed level of the lower knife, which, if the shape of the material varies, requires cumbersome and expensive handling equipment.

It is an object of the invention to provide an improved shear in which a change of knives will cause a minimum of down time.

It is also an object of the invention to provide a vertical shear in which the upper and lower knives may be changed, as well as aligned with each other, outside the machine in a simple manner.

It is another object of the invention to provide a shear with an integrated knife assembly in which cutting movements may be simulated outside of the shear for precise alignment of the knives.

Another object of the invention is to provide a vertical shear in which the upper knife system cooperates with its actuator merely under resilient pressure without being fastened thereto so that the upper knife system may be readily separated from its actuator.

Still another object of the invention is to minimize the transmission of eccentric forces from the reciprocating knife system of a shear to the actuator thereof, and practically to eliminate play between the reciprocating parts during operation.

A further object of the invention is to equip a vertical shear with a plurality of interchangeable assemblies which are used in rotation, and each of which comprises a complete set of upper and lower knives.

It is a still further object of the invention to provide a vertical shear with a movable lower knife holder and compact means for positioning the holder at a desired level prior to a shearing operation.

2

Various other objects, features and advantages of the invention will become apparent as the description proceeds.

In the drawings which illustrate an embodiment of the invention by way of example,

5 FIG. 1 shows a vertical shear according to the invention in section taken generally along line 1—1 of FIG. 3, certain parts being broken away for better illustration; FIG. 2 shows a portion of FIG. 1, some of the parts being in different positions for cutting another size of

10 material; FIG. 3 is an enlarged section taken generally along line 3—3 of FIG. 1, but showing some of the parts in the FIG. 2 position, the material to be sheared being omitted;

15 FIG. 4 is a plan view taken in the direction of the arrow 4 of FIG. 1, certain parts being broken away for better illustration;

FIG. 5 is an enlarged, fragmentary section taken along line 5—5 of FIG. 4;

20 FIG. 6 is an enlarged, fragmentary section taken along line 6—6 of FIG. 1;

FIG. 7 is an enlarged, fragmentary section taken along line 7—7 of FIG. 6; and

25 FIG. 8 is an enlarged, fragmentary section showing a detail.

Referring to the drawings, an upright housing or frame generally indicated at 10 and mounted on a foundation block 11 is adjacent its top equipped with split bearings 12 for journailling a crankshaft 14 which has a connecting rod 16 attached thereto to operate a knife actuator or ram 20 reciprocable in vertical guideways 22 of the frame. It will be clear that instead of the mechanical drive 14, 16, hydraulic operating means may be provided if desired.

30 35 Below its vertical guideways 22, the frame 10 has a large opening 24 therethrough in which horizontal guideways 26 (FIG. 3) are positioned to accommodate a carriage generally indicated at 30. The latter is interchangeable and used in rotation with similar carriages, one of which is indicated at 31 in FIG. 4. An upper knife 34 and its backer 35 (FIG. 3) are secured at 37 (FIG. 1) to an upper knife holder 36 which is vertically movable in guideways 38 positioned particularly in the corner regions of carriage 30. The upper knife holder

40 45 has a raised portion 39 at its top for engaging the ram 20 and normally is resiliently urged upwardly by biasing means such as four cylinder and piston units 40 arranged adjacent the four corners of the knife holder. Each of

50 55 the units 40 which are single-acting comprises a cylinder 41 (FIG. 5) mounted in a bore 42 of the upper knife holder and secured to the latter at 42A, a cylinder head 43 fastened at 43A, a piston 44, and a piston rod 45, each cylinder having an upper chamber 46. The lower ends 47 of the piston rods are spherically shaped and supported on mating surfaces of replaceable wear disks 48 (FIG. 3) inserted in carriage 30.

Attached to lateral ports 49 (FIG. 5) of the cylinder heads 43 are pipes 50 (see carriage 31, FIG. 4) which are positioned in grooves 51 of the upper knife holder 36 and connected to a common pipe line 52 accommodated in a groove 53 of the upper knife holder. A conventional quick disconnect coupling comprising portions or halves 54, 55 (see carriage 30, FIG. 4) serves for the attachment to pipe line 52 of a flexible hose 56 which is in turn connected to a pipe line 57 leading to a source of pressure such as an accumulator 58 containing oil under pneumatic pressure.

60 65 Conventional hold-down or stripper pins 60 (FIG. 3) are movable in bushed bores 61 of the upper knife holder 36 against the pressure of springs 62. Nuts 63 attached

to the threaded upper ends of the pins serve to limit downward movement of the pins relative to the knife holder 36.

A lower knife 64 and its backer 65 are secured at 67 (FIG. 1) to a lower knife holder 66 which is vertically movable in guideways 68 of carriage 30. The knife holder 66 is provided with upwardly extending portions 69 for better guidance and with lateral projections 70, 71 (FIG. 3) which in the lowermost position of the knife holder rest on shoulders 72, 73 of the carriage. These shoulders terminate in inclined faces 74, 75 which cooperate with shields 76 made of plate material and mounted on the frame 10 to deflect pieces of metal dropping down during a shearing operation. Mechanism for lifting the lower knife holder to a level above its rest position will be described later.

A pair of spaced track members 80, 81 are attached at one end to frame 10 by fastening means 84 (FIG. 6) while the other ends of the track members are secured by fastening means 86 (FIGS. 1 and 4) to a base 90 mounted on a foundation block 91 so that the members 80, 81 bridge the space between blocks 11 and 91. The track members have guideways 94 aligned with the guideways 26 of frame 10 and forming a continuous track therewith so that the carriage 30 may readily be shifted on this track from the cutting station in frame 10 onto the members 80, 81 and vice versa. For such movements, a driving mechanism is provided comprising a reversible electric motor 96 attached to a gear unit 93 which is mounted on the base 90; a brake 99 for stopping the mechanism at a desired instant; a threaded spindle 100 rotatable by means of unit 98 and arranged in the space between the track members 80, 81; a travelling nut 102 meshing with spindle 100 and engaging guideways 103 of the track members; and a pin 104 secured to the top of nut 102. One end of spindle 100 is journaled in the base 90 and the other end is supported in a bearing 108 which is secured to the track members 80, 81 at 109 (FIG. 6). The carriage 30 has a rearward extension 110 provided with a hole 112 into which the pin 104 projects. Since the spindle 100 is secured against axial movement by reason of its attachment to gear unit 98 at 114 and by means such as its shoulder 116 (FIG. 1), and since the travelling nut 102 is prevented from rotating due to its engagement with guideways 103, the nut 104 and carriage 30 will be caused to move along the track in a selected direction when spindle 100 is turned in a corresponding way.

To determine the shearing position positively, the carriage 30 is provided with two lateral arms 118 which stop inward movement of the carriage upon engagement with frame 10. The arms have holes 120 (FIG. 7) therein to receive pins 122 secured to the frame. Tapered keys 124 provided with eyebolts 125, and keyways 126 in the pins serve to lock carriage 30 releasably in its shearing position.

Referring now again to the lower knife holder arrangement, mechanism for lifting the knife holder 66 from its rest position comprises a slide 130 (FIGS. 1 and 3) mounted for vertical movement in guideways 132 of the frame. The slide 130 has a recess 134 at its bottom and is provided with an inclined guideway 136 mating with the top of a wedge 140 which is accommodated in the recess 134. The wedge having a liner 142 at its bottom is movable on a horizontal face 144 in an opening 146 (FIG. 3) which extends through frame 10 at right angles to the path of travel of carriage 30. A pressure-operated, double-acting cylinder and piston unit 148 is mounted on frame 10 and connected to one end of the wedge to move the latter. Facing the other end of the wedge is an abutment member in the form of a threaded rod 150 which is supported in a pillow block 152 mounted on frame 10. Rod 150 is axially shiftable to a selected position relative to pillow block 152 by means such as a worm drive located at 154 in a lug of the pillow block.

An auxiliary, relatively long flexible hose 172 (FIG. 14) is equipped with a coupling portion 175 identical with

portion 55. The hose 172 is connected to a pipe line 176 which includes a manually controlled exhaust or bleeder valve 177 and leads to an auxiliary source of pressure such as a pump unit 178.

Operation

When carriage 30 is in its cutting position shown in full lines in FIG. 1, both knife holders 36 and 66 are aligned with the ram or actuator 20. The chambers 46 of cylinders 41 communicate freely with the accumulator 58 so that the upper knife holder is urged upwardly and its top 39 is in engagement with actuator 20. The lower knife holder 66 may rest on the shoulders 72, 73 of the frame as shown in FIG. 1. As the knives, 34, 64 are shaped for triple cuts, three elements such as angles 180 (FIG. 1) may be placed in the machine simultaneously. When crankshaft 14 is turned and the actuator 20 descends to perform the shearing operation, the cylinders 41 will be caused to move downwardly over their pistons 44 so that fluid under pressure will be forced to flow from chambers 46 back to the accumulator. When the cut has been completed and ram 20 ascends again, fluid will return from the accumulator to the cylinders 41 and cause them to move upwardly over their pistons 44 so that the upper knife holder 36 will follow the upward motion of the ram in engagement therewith. It should be noted that chambers 182 (FIG. 5) in cylinders 41 are connected to the atmosphere through ports 183 and clearance 184 at the circumference of the cylinders to allow for free flow of air to and from these lower chambers.

To guide knife 34 safely when it approaches knife 64, each of the upwardly extending portions 69 of the lower knife holder has a recess or guideway 186 therein as shown in cross-section in FIG. 8. These guideways cooperate with lateral extensions 187 on the upper knife holder 36.

During the downward movement of knife 34, the hold-down pins 69 will engage the angles 180 in conventional manner and firmly bear thereupon under the pressure of their springs 62 to avoid tilting of the angles. At this stage the pins are stopped from further participation in the downward movement of the upper knife holder and its drive. Therefore, holes 188 (FIG. 3) are provided in ram 20 to accommodate the upper ends of the pins, as well as their nuts 63 which are disengaged from the upper knife holder 36 at this time. When knife 34 starts to move upwards upon completion of the cut, the pressure exerted by pins 69 will counteract any tendency of the angles 180 to stick to the knife and will be effective to strip the angles therefrom as well known in the art. At a predetermined point of the upward stroke of knife 34, the nuts 63 are engaged again by knife holder 36 and the stripper pins are then lifted together with the holder. The shearing operation may then be repeated after further material to be cut has been placed on the lower knife.

When it is necessary to change the knives due to a change in the shape of the material to be handled or for other reasons, the tapered keys 124 are removed from their pins 122 and the flexible hose 56 is disconnected from pipe line 52. The halves 54, 55 have built-in check valves 190, 192 which, upon disconnection of the coupling, close automatically to seal the cylinders 41 as well as the accumulator 58 so that uncontrolled escape of fluid is prevented. The coupling portion 175 positioned on the auxiliary hose 172 and having a built-in check valve 194 is now connected to coupling portion 54, which by reason of the construction of these standard parts will result in both check valves 190, 194 being automatically pushed to open positions. The manually operated bleeder valve 177 is then opened temporarily with the pump 178 being shut off to release a small amount of fluid from cylinders 41 so that the upper knife holder 36 will descend slightly due to the action of gravity and thus will be disengaged from ram 20. Thereafter, hose 172 may be disconnected from the carriage. Slide 130 and wedge 140 should be in their withdrawn positions at this time. Motor 96 is started to move carriage 30 along track mem-

bers 80, 81 from the cutting or shearing station where the carriage is in the position shown in full lines in FIG. 1, to a transfer station where the carriage is in the withdrawn position indicated in phantom at 30' in FIG. 1. Lifting equipment such as a crane is connected to hooks 193 on carriage 30 to raise the latter from the track and move it to a convenient location on the floor. Pin 104 of the travel mechanism is readily released from engagement with hole 112 when the carriage is lifted.

The next carriage 31 having the required knives attached thereto ready for operation is then raised by means of the crane and placed on the track so that its hole 112 accommodates pin 104. The cylinders 41 of carriage 31 contain a predetermined amount of fluid and their position is such that the top of the upper knife holder will clear ram 20. Motor 96 is now started in the reverse direction to move carriage 31 into the shear frame and is then stopped and the brake 99 is applied to bring the arms 118 of carriage 31 into smooth engagement with frame 10, whereupon the tapered keys 124 are inserted in pins 122 to lock the carriage in position. Flexible hose 56 is connected to carriage 31 and thereby both check valves 190, 192 of the coupling will be automatically pushed to open positions so that the cylinders 41 will communicate freely with the accumulator 58 and additional fluid under pressure will enter the chambers 46 to bring the upper knife holder 36 of carriage 31 into engagement with ram 20. The cylinders 41 will communicate continuously with the accumulator while the flexible hose 56 remains connected to the carriage. The shear is now ready again for operation with the lower knife holder 66 being in its rest position on shoulders 72, 73 of carriage 31.

While operation of the shear is resumed after a minimum of down time and proceeds without interruption, a knife change may be performed on the withdrawn carriage 30 in accordance with the requirements of the production program. After the upper and lower knives have been changed, they can be completely aligned with each other in the withdrawn carriage which is outside the shear on the floor where the parts are easily accessible. For this purpose, the auxiliary hose 172 may be connected to pipe 52 on carriage 30 and the upper knife holder of this withdrawn carriage may then be reciprocated with the aid of bleeder valve 177 and pump unit 178 to perform idle movements, that is, to simulate the shearing motion. This renders it possible to check the alignments of the parts outside the shear frame. Before the auxiliary hose 172 is disconnected from the withdrawn carriage, the cylinders 41 thereof are partly but not entirely filled with fluid by means of pump unit 178 so that the upper knife holder 36 of this carriage is in the proper position to clear ram 20 when carriage 30 is moved into the shear again upon withdrawal of carriage 31.

The reason for the movable arrangement of the lower knife holder 66 will be best understood from a comparison of FIGS. 1 and 2. In FIG. 1, the lower knife holder is in its rest position to shear the relatively small angles 180 which are advanced to the shear on a feeding table and then received on a depressible delivery table, the normal level of the tables being indicated in chain lines at 202. In the case of larger angles 204 (see FIG. 2) the legs thereof extend further downwards. Therefore, in conventional shears having the lower knife in a fixed vertical position, it is necessary to make the feeding and delivery tables vertically shiftable and lower the tables when larger angles are handled, so that the inner contour of the angles will properly register with the top of the lower knife. As the feeding and delivery tables are relatively long and heavy and, moreover, the delivery table is depressible, shiftable supports for such tables are cumbersome and relatively expensive. The movable arrangement of the lower knife eliminates these drawbacks since

only one single, compact assembly need be shifted as will be clear from the following description.

Wedge 140 is initially in its withdrawn position shown in phantom at 140' in FIG. 3 and, accordingly, slide 130 is in its lowermost position as shown in phantom at 130' in FIG. 3. This initial arrangement of the parts is illustrated in full lines in FIG. 1 and it will be seen that the top surface of slide 130 now clears the lower knife holder 66 and the carriage 30 by a predetermined distance so that the carriage may be moved along its track. At the same time, the lower knife is in its proper position for shearing the small angles 180 shown in FIG. 1. For cutting the larger angles 204, the threaded rod 150 is moved axially by means of worm drive 154 to a predetermined extent, which may be done while the carriage 30 is within or outside the frame 10. When the carriage is in the frame, pressure is admitted to the cylinder and piston unit 148 to move the far end of wedge 140 into engagement with the adjacent end of rod 150 and lift slide 130 a corresponding distance. The top of the slide will thereby engage the bottom of the lower knife holder 66 and shift the latter to the desired level as shown in full lines in FIGS. 2 and 3. It may be mentioned here that the total vertical movement of slide 130 is somewhat larger than that of the lower knife holder as there is initial clearance between these parts. Slide 130 and wedge 140 may be withdrawn by admitting pressure to the return side of unit 148 whenever required. It will be clear that with this arrangement small and large angles may be fed to the shear at the same level 202 and will be discharged at the same general level so that it is no longer necessary to shift the feeding table and the depressible delivery table upon a change in the angle size.

The removal of a carriage assembly from the shear 35 and the replacement thereof by another completely assembled carriage can be achieved very rapidly. Operation of the machine is interrupted for a brief period of time only since the upper knife holder 36 is not fastened to its actuator 20 and is disengageable therefrom simply by operating the cylinder and piston units 40. Rod 150 may be preset while the exchange of carriages takes place so that wedge 140 and slide 130 can be actuated to bring the lower knife to the desired level as soon as the respective carriage is locked to frame 10. On a large shear built according to the invention and capable of exerting a shearing force of 700 tons, the changeover has been carried out within seven minutes. As compared therewith, a complete change of upper and lower knives including alignment causes five hours down time in one 50 conventional type of shear while eight hours are required in another type.

It should be noted that as the upper knife holder is not rigidly connected to the ram but is guided in the carriage, no appreciable eccentric forces will be transmitted to the ram which has a beneficial effect upon the operation of the shear drive. Further, the resilient pressure exerted by the cylinders 41 will practically eliminate play between the reciprocating parts so that they will operate smoothly.

As will be understood, the embodiment described 60 herein does not illustrate all the ways in which the broad invention may be employed. In case of a relatively simple production program, for example, it may not be necessary to make the lower knife movable relative to carriage 30 or 31. The basic advantages of the carriage 65 will be obtained regardless of whether the lower knife is rigidly or movably mounted thereon, though the latter arrangement is superior where a large variety of different shapes is to be handled.

Other possible modifications relate to the hydraulic 70 means. A bleeder or control valve may be provided on the upper knife holder proper so that the latter may be lowered readily without connecting the auxiliary hose 172 thereto. Further, a single source of pressure and suitable control valves may replace the two separate hydraulic systems and bleeder valve shown in the drawings

as will be readily clear to those skilled in the art. Structural details may likewise be changed in that, for example, the pistons 44 may operate in bores of the upper knife holder proper though the use of separate cylinders is preferable, or the pistons may be attached to the upper knife holder and the cylinders may then be supported on the carriage. Various other modifications and changes may be made without departing from the scope of the invention as defined in the appended claims.

Having described my invention, what I claim and desire to secure by Letters Patent is:

1. A vertical shear for cutting billets, beams and the like, comprising a source of fluid under pressure, a frame, an actuator mounted in said frame for reciprocation along a substantially vertical axis, operating means on said frame for reciprocating said actuator, substantially horizontal guide means intersecting said axis and extending from a cutting station in said frame to a transfer station remote therefrom, an assembly movable on said guide means independently of said actuator between said cutting and transfer stations; said assembly including a carriage, an upper knife holder mounted in said carriage for substantially vertical movement, an upper knife secured to said holder, a lower knife arranged on said carriage for cooperation with said upper knife, and cylinder and piston means supported on said carriage and connectible to said source, said cylinder and piston means being operable at the cutting station to urge said upper knife holder resiliently towards said actuator for engagement therewith; and a valve for releasing a selected amount of fluid from said cylinder and piston means to disengage said upper knife holder from its actuator prior to withdrawal of the carriage from the cutting station; said assembly being removable from said guide means at the transfer station as a unit whereby said assembly may be replaced by another carriage assembly interchangeable therewith.

2. A shear as specified in claim 1, including conduit means connecting said source to said cylinder and piston means and establishing continuous communication therebetween while said carriage is at the cutting station.

3. A shear as specified in claim 1, including conduit and valve means operable when said carriage is outside said frame to introduce fluid under pressure into said cylinder and piston means and then to withdraw fluid therefrom to perform idle movements of the upper knife holder and knife.

4. A vertical shear for cutting billets, beams and the like, comprising a frame, an actuator mounted in said

frame for reciprocation along a substantially vertical axis, operating means on said frame for reciprocating said actuator, a substantially horizontal guide means intersecting said axis, an assembly movable on said guide means independently of said actuator between a cutting station in said frame and a transfer station remote therefrom; said assembly including a carriage, an upper knife holder mounted in said carriage for substantially vertical movement, an upper knife secured to said holder, biasing means supported on the carriage and operative at the cutting station to urge said upper knife holder resiliently towards said actuator for effective engagement therewith, a lower knife for cooperation with said upper knife, a lower knife holder supporting said lower knife and mounted in said carriage for substantially vertical movement relative thereto, and abutment means on the carriage for supporting said lower knife holder in a lower rest position, said assembly being removable from said guide means at the transfer station as a unit; and positioning means mounted on said stationary frame and engageable with the lower knife holder for lifting said lower knife holder from its lower rest position and returning it thereto; whereby said assembly may be replaced by another carriage assembly interchangeable therewith at the transfer station and said lower knife holder with the lower knife thereon may be shifted to a selected level at the cutting station prior to a cutting operation.

5. A shear as specified in claim 4, in which said positioning means include a slide mounted in said frame for substantially vertical movement, and said carriage has a downwardly open slideway therein accommodating the lower knife holder, said slide being arranged to enter said slideway and to engage said lower knife holder when said carriage is at the cutting station, power-operated, actuating means being supported on said frame for causing said slide to shift said lower knife holder a predetermined distance.
